OVERVOLTAGE PROTECTED INDUCTION APPARATUS

Jack R. Meador, Pittsfield, Mass., assignor to General Electric Company, a corporation of New York

Application August 31, 1951, Serial No. 244,541

2 Claims. (Cl. 317—15)

This invention relates to electromagnetic induction apparatus, such as high voltage power transformers, and more particularly to overvoltage protection thereof.

Heretofore, the better grades of high voltage transformers have been provided with two kinds of overvoltage protection, simultaneously. That is, internal electrostatic shields to avoid voltage concentrations and resonance phenomena and external lightning arresters to avoid excessive voltages at the terminals of the winding. Although well protected high voltage transformers can and have been made by this method, the method is not free from various limitations and disadvantages, which the present invention aims to overcome. For instance, considering the factor of shielding, adequate electrostatic shielding has been found applicable so far only to limited types of windings, and only in a limited class of circuit connections, so that certain winding arrangements desirable for other purposes have either had to be dispensed with or used with inadequate shielding. Furthermore, the successful performance of a shield depends on the successful adaptation of the shield design to the characteristics of the winding itself, requiring great design skill, and not all of the so-called "shielded" windings have necessarily the hoped-for impulse voltage distribution. It follows that no standardized shield may be applied to any and all high voltage windings and be expected to do well what it is intended to do, regardless of the type of design of the winding. The nature of the overvoltages and the protection problems involved in such cases are explained in my United States Patent No. 2,276,855, which explains also the limitations of electrostatic shields as applied to them. That patent discloses a protective arrangement, the main feature of which is the application of a plurality of nonlinear resistance shunts between taps along the winding. That arrangement represents the best in the prior art that I know of, and it has been used effectively and successfully in a number of such cases. However, I find that it has certain limitations in that the shunt resistors are a constant drain on the current and energy of the circuits. In order to reduce this wastage to tolerance values, the resistance values must be increased, and this tends to lower the protection which they afford.

Concerning the lightning arrester, although good arresters are available as such, yet by virtue of their design as an independent piece of apparatus, they cannot discriminate between the different kinds of overvoltages and the different classes and types of equipment for which they are to provide protection. Neither can they take substantial advantage of possible help from the protected apparatus. For example, when a lightning arrester made up of several elements, each comprising a gap in series with a current limiting resistor, is connected to a high voltage circuit, the voltage distribution among the elements, in the absence of a discharge current, is determined by their capacitances to each other and to ground. This generally tends to be some undesired function, and, therefore, auxiliary means have to be provided to improve this distribution. Even with such auxiliary means, some of the standard arresters are sensitive to changes in their exposure to ground and their protective value may be lowered by unappreciated unfavorable electrostatic exposures in various installations. Under impulse conditions, it is expected of an arrester that it discharge an excessive overvoltage without time lag. However, for very steep impulses, arrester gaps do have a time lag, and various types of auxiliaries are utilized in the arrester art to reduce this time lag and resulting over-

2

voltage. Nevertheless, in the leading types of the present day arresters with such auxiliaries, the impulse discharge voltage for the standard AIEE impulse wave is about twice as high as the normal frequency spark over voltage of the arrester.

It is, therefore, an object of the present invention, to provide a protective arrangement in which electrostatic shields can be dispensed with altogether, thereby eliminating all such limitations in winding design or circuit connection, as well as expense of shielding.

It is also an object of the present invention to provide a protective arrangement in which the lightning arrester can be assisted by the protected apparatus to make the response of the arrester more selective and positive, improve the protection, and simplify the arrester structure.

The invention will be better understood from the following description when taken in connection with the accompanying drawing and the scope of the invention will be pointed out in the appended claims. In the drawing, Fig. 1 illustrates a side elevation view partly in section of an induction apparatus and an arrangement for the protection thereof in accordance with the invention; Fig. 2 is a schematic diagram illustrating the circuit layout in the arrangement illustrated in Fig. 1 and Fig. 3 is an enlarged cross-sectional view of a protective element shown in Fig. 1.

Referring now more specifically to the details of the figures, a representative two-legged core-type high-voltage transformer in combination with the overvoltage protective means of the present invention is shown mounted in a tank or container 10 filled with an insulating oil or liquid 11. Transformer windings 12 and 13 are arranged in two stacks respectively on the two legs of a magnetic core and are connected in parallel and submerged along with the core in the insulating fluid 11. The numeral 14 identifies the line terminal of the windings while the other terminal 15 is shown as grounded although it may be connected to a line circuit. A plurality of protector elements 17 comprising an arrester protective device are stacked end to end in electrical contact with each other in a tube 16 of insulating material and positioned closely adjacent to windings 12 and 13 with the longitudinal axis of the tube and the common axis of the stack of elements 17 substantially parallel to the axis of the winding. A portion of tube 16 has been shown cut away to expose to view the lightning arrester protector elements which have an over-all length substantially equal to the portion of the winding leg along which the winding is disposed and are so positioned in the tube that the end element at one end of the stack is disposed opposite and closely adjacent one end of the winding and the end element at the other end of the stack is disposed opposite and closely adjacent the other or opposite end of the winding. Relatively short electrical conductors extending through openings in tube 16 electrically connect the end elements of the stack respectively to the winding ends adjacent and opposite thereto while a plurality of similarly short conductors or cross connections 30, also extending through openings in the tube, electrically interconnect the junction between each pair of elements 17, intermediate the ends of the stack, to a corresponding point of each winding located, intermediate the ends of the winding, at approximately the same distance as the junction to which it is connected is located from an end of the winding. Corresponding points here means points that are intended to have the same potential under operating conditions and the shortness of these cross connections assures that the pair of points so interconnected shall have their potential alike under impulse conditions also. The tube 16 is located in such a position that each of the short conductors 30 is of substantially equal length.

As better illustrated by Fig. 3, each of the arrester elements comprise an arc gap 18 connected electrically in series with a resistor disk 19, preferably of the non-linear type. Gap 18 is defined by a pair of electrodes 20 and 21, respectively part of metal disks 22 and 23, maintained spaced or separated by a spacer of insulating material such as porcelain ring 24. The resistance and gap in series therewith are hermetically sealed within a chamber or enclosure comprising a glass ring 25 with an end wall plate 26 of metal conducting material sealed thereto by

fusion. A metal collar 27 is also sealed by fusion to the opposite end of the glass ring 25 and another end wall plate 28 of metal conducting material is welded to metal collar 27. Element 29 represents a metal plate and resilient spring of conductive material by means of which the electrode-resistor assembly are maintained by pressure in good electrical contact with end or terminal plates 26 and 28. The free space within the element or unit 17 is filled with a dry or inert gas, such as nitrogen, at a pressure most suitable for the voltage class for which the arrester unit is designed. The sealed unit maintains the gas density and hence the gap breakdown voltage practically constant, independent of variations of temperature and pressure. In a conventional lightning arrester, generally freely ventilated or at least capable of "breathing," the gas density at the gaps may vary by as much as 30% due to variations in the atmospheric temperature and pressure, with corresponding changes in the breakdown voltage of the gaps. The submersion of the arrester within the transformer liquid also prevents wide and rapid fluctuations of temperature and the resulting physical strains to which the conventional arrester insulations exposed to the weather are subjected. Thus it will be seen that the protective arrangement generally speaking involves a lightning arrester connected between the line side of a winding and the other end or side thereof but preferably to ground and comprises a plurality of series connected protector elements each consisting of a resistor connected in series with an air gap and with the junction between each of the elements connected by relatively short leads to spaced points along the winding to be protected. In contrast to prior practice where shields have been employed to reduce voltage concentration, it should be noted that in the present case, any excess local over-voltage is discharged, not merely reduced or distributed. Furthermore, in the present arrangement there is, normally, no leakage of current through the protective shunts and, therefore, the resistance elements can be set for much lower values than in the older schemes involving merely resistance shunts between taps along the winding. In this connection, I have found that the overvoltages permitted by the older schemes can be reduced in the ratio as much as 5 to 1 by the novel means of the present invention.

The arrangement of the winding and the arrester with a plurality of cross connections between them makes the arrester highly selective and sensitive to those transient types of overvoltages which tend to produce voltage concentrations within the winding and discharges them at a lower terminal voltage than other types of impressed overvoltages which do not cause similar voltage concentration and thus dependable overvoltage protection is provided for each portion of a protected winding regardless of the type of overvoltage to which it may be subjected and regardless of what its individual voltage distribution characteristics may be. This result follows from the fact that excessive voltage concentration across any portion of the winding, due to the omission of electrostatic shields, causes the corresponding arrester element to discharge and as the total voltage is then impressed across a smaller number of gaps, the remaining gaps are also caused to discharge. That is, the discharging of one of the arrester elements acts as a trigger to cause the entire arrester to discharge. Thus, no particular auxiliaries are required for the gaps to improve their discharge characteristics in this respect, as this function is effectively served by the high voltage winding with which the arrester is interconnected at a plurality of points. As the impulse voltages associated with appreciable time lag in the discharge gaps are also those that tend to produce a nonuniform voltage distribution and local voltage concentrations in the windings, therefore, when the winding and the arrester are interconnected at a plurality of corresponding points, a voltage concentration across a portion of the winding appears also as a voltage concentration across the corresponding portion of the arrester. As this portion of the arrester discharges, it throws the overvoltage across the remainder of the arrester, which now is overstressed more than before, and thus, progressively (though very fast) the entire arrester discharges. It may be seen that, in this arrangement, the more nonlinear the initial voltage distribution in the winding, the lower will be the terminal value of the overvoltage which the arrester will discharge. That is, in this arrangement, the arrester is highly responsive to the specific needs of any given winding to be pro-

ected, and provides equivalent protection to all, without being designed for the peculiarities of any particular winding with respect to impulse voltages. Because of this action the auxiliary structures provided in conventional arresters for control of their voltage distribution is dispensed with, thus resulting in the greatly simplified arrester structure illustrated. In addition, various other auxiliaries provided in conventional arresters to cause ionization and thereby render their discharge characteristics more prompt, positive and dependable, have also been dispensed with. Although the discharging of an arrester element is theoretically preceded by an overvoltage in the corresponding portion of the winding, this is nothing to be concerned about because it is only an attempted overvoltage and cannot rise above what the gap involved will permit. It actually represents a smaller strain in the winding than what can exist in those shielded designs in which the voltage distribution within the winding may have cusps or other sharp local irregularities not under direct control or protection by an arrester element in shunt for that portion of the winding.

A further important beneficial effect of the present arrangement on the performance of the arrester is that in the conventional practice, in which the arrester is mounted external to the transformer, the arrester is some distance from the protected winding, and the standard rules of the American Institute of Electrical Engineers permits a separation of as much as 75 feet. However, based on some recent experiences and tests, I am convinced that even a 25 foot separation may result in as much as 20% difference between the terminal impulse overvoltages of the arrester and the winding. In view of the close proximity of the arrester to the winding and the relatively short cross connections, such difference is obviously impossible in the present arrangement.

While I have, in accordance with the patent statutes, shown and described a particular embodiment of my invention, it will be obvious that changes and modifications can be made without departing from the invention in its broader aspects and, I, therefore, aim in the appended claims to cover all such changes and modifications as fall within the true spirit and scope of the invention.

What I claim as new and desire to secure by Letters Patent of the United States is:

1. Electromagnetic induction apparatus comprising a container, insulating fluid in said container, a magnetic core having a pair of spaced winding legs submerged in said fluid, said winding legs having their axes in substantially parallel relationship, a winding disposed longitudinally along each of said submerged winding legs, said windings being electrically connected in parallel, an insulating tube in said fluid mounted closely adjacent each of said windings with the longitudinal axis of said tube substantially parallel to the axes of said windings, a plurality of lightning arrester elements mounted end to end in said tube and electrically connected in series, each element comprising a series connected gap hermetically sealed within an enclosure, said plurality of elements having an overall length substantially equal to the portion of said winding legs along which said windings are disposed and so positioned in said tube that the end elements are respectively located adjacent opposite ends of said windings, and electrical conductors extending through openings in said tube and connecting the end elements to the winding ends adjacent thereto and the junction between a pair of said elements to points on each of said windings adjacent thereto, said tube being located in such a position that each of said conductors is of substantially equal length.
2. The apparatus of claim 1 in which the sealed elements of said lightning arrester are further characterized by said enclosure being formed of a hollow vitreous member and a pair of flanged metallic end walls, said flanges being sealed to said vitreous member by fusion.
